UNITED STATES PATENT OFFICE.

DANIEL HANDELAN, OF MINNEAPOLIS, MINNESOTA.

AIR-MOISTENING APPARATUS FOR HOT-AIR FURNACES.

Application filed September 1, 1926. Serial No. 132,955.

My invention relates to air moistening apparatus for hot air furnaces and to furnace shoes for use in conjunction with such air moistening and humidifying systems applicable to furnaces and particularly to the type of air moistening and humidifying system having a spray nozzle within the cold air return duct of the furnace.

An object of the invention is to provide a shoe by means of which the surplus water discharged into the shoe may be readily and conveniently disposed of before the same enters the furnace so that unnecessary corrosion of the furnace proper may be prevented.

Another object of the invention resides in providing a shoe curved at one end and formed at its other end with a neck having the bottom thereof raised above the base of said shoe, said neck being directly connected to the casing of the furnace and serving to prevent the water accumulating in the bottom of the shoe from entering the space within the furnace.

Another object of the invention resides in providing an inclined baffle situated within the furnace and inclining toward the inner wall of the furnace, said baffle having a drain-board connected therewith adapted to lie upon the bottom of the neck and extending into the shoe proper for collecting and turning all water precipitated against said baffle back again into the shoe.

A still further object of the invention resides in employing an annular sleeve for the reception of the cold air return duct of the furnace, which sleeve is arranged with a portion depending within the shoe, having formed along its lower edge an annular gutter adapted to receive and collect all the surplus water deposited upon the wall of the duct and to further provide a leader connected with said gutter for discharging the water collected thereby into the bottom of the shoe adjacent the waste pipe associated therewith.

With the foregoing and other objects in view, which will appear in the following description, the invention resides in the novel combination and arrangement of parts and in the details of construction hereinafter described and claimed.

In the drawings illustrating an embodiment of my invention:

Fig. 1 is a fragmentary elevational view of a furnace and cold air return therefor illustrating the application of my improved

air moistening apparatus thereto, and showing a portion thereof and said cold air duct in section.

Fig. 2 is a plan sectional view taken on line 2—2 of Fig. 1.

Fig. 3 is an enlarged sectional detail view of the sleeve and gutter mounted on the top of the shoe.

With the ordinary humidifying system, such as are used in conjunction with furnaces where the moisture is sprayed into the cold air return duct of the furnace, considerable difficulty has been encountered due to the fact that the surplus water enters the furnace proper and rapidly causes the corrosion of the interior walls of the same. In addition surplus water in large particles follows along with the air and is deposited within the rooms whose air is being humidified, thereby moistening the articles within such rooms and causing disfigurement and injury to the same. My invention overcomes these difficulties by providing a structure adapted to remove both the surplus water from the cold air duct and the shoe, as well as from the air entering the furnace so that when the air is discharged into the room proper said air is of uniform humidity and the particles of water suspended therein are sufficiently fine to prevent injury or disfigurement to the articles within the room, at the same time preventing the corrosion of the interior of the furnace.

For the purpose of illustrating the application of my invention I have shown a portion of a furnace indicated in its entirety at A. This furnace consists of the usual ash pit and fire box sections 10 and 11 respectively supporting the grates 12 in the ordinary manner. A circular casing or shield 13 encircles the exterior of the furnace forming an annular space 14 extending completely around the same for the reception of the air to be heated, said space being connected with the usual hot air pipes at the top of the furnace which have not been shown in the drawings. A cold air return duct 15 is connected with the rooms whose air is to be heated and humidified, and extends downwardly towards the bottom of the furnace where the same is connected therewith by means of my improved shoe as will presently become apparent.

Within the cold air return duct 15 at a point considerably above the floor on which the furnace rests is situated a spray nozzle

16 connected by means of a pipe 17 to any suitable water supply system. This nozzle 16 is of a type adapted to break up the water passing therethrough into a fine mist, 5 and to discharge the same downwardly in the direction of travel of the cold air being returned to the furnace. The mist emanating from the nozzle 16 spreads out and is directed against the walls of the duct 15 10 where a portion of the same is precipitated and caused to flow along the inner walls of said duct as water. In addition to this water a certain amount of the mist or vapor discharged from said nozzle consists of 15 larger globules which are sufficiently heavy so that when the velocity of the air subsides the same are caused to precipitate upon the articles with which the air comes in contact. This water, together with the water formed 20 along the inner walls of the duct 15, is collected by means of my invention and discharged into a suitable waste, as will now be explained.

The duct 15 is connected to the lower end 25 of the casing 13 of furnace A by means of a shoe indicated in its entirety at B. This shoe consists of side walls 18 and 19 connected by a curved rear wall 20. A base 21 forms a bottom for the said walls while a 30 top 22 covers the upper portion of the same. At the end of the shoe opposite the wall 20, the top 22, the side walls 18 and 19, and a bottom 23 elevated above the base 21 form a neck 24 adapted to be connected with the casing 13 and to communicate with the interior of the furnace through an opening 25 formed in said casing. The bottom 23 of this neck is connected by means of a short wall 26 extending completely across the shoe 40 from wall 18 to wall 19 to the base 21, thus forming a compartment or pan 27 in the bottom of the shoe B into which the surplus water collected from the humidifying system may be discharged. This compartment 45 is drained by means of a waste pipe 28 connected to the base 21 thereof which may lead to any suitable sewer or sump.

The lower end of the vertical cold air return duct 15 is connected to a sleeve 29 which 50 is mounted upon the shoe B and is shown in detail in Fig. 3. This sleeve is circular in formation and consists of an inner lining 30 surrounded by an outer covering 31 extending only for a portion of the length thereof. 55 The lower end of the covering 31 is doubled back as indicated at 32 to form a shoulder 33 at the bottom thereof, while the upper part thereof may be integrally formed with the lining 30 or the same may be secured thereto in any suitable manner. An opening 60 is cut in the top 22 of shoe B concentric with the curved wall 20 of said shoe and of such dimensions as to snugly receive the inner lining 30 of sleeve 29 so that the 65 shoulder 33 of the covering 31 rests upon the

marginal portion 34 of said top so as to support and hold the same in place. It will be noted that the lower portion of the lining 30 extends downwardly within the shoe B where the same is turned up as indicated at 70 35 to form an annular gutter 36 extending completely around the same. The sleeve 29 is attached to the top 22 by soldering the same within the interior of the shoe at 75 37. It will be noted that the bent-up portion 35 of the sleeve 29 forming a gutter 36 is arranged so that the same inclines toward the center of the curved wall 20 of the shoe. The lowermost portion of gutter 36 has attached to it a leader 38 adapted to receive the water 80 collected by said gutter and discharge the same in the compartment 27 at the bottom of said shoe in close proximity to the waste pipe 28. The cold air return duct 15 is formed with the usual bead 39 running circumferentially about the same at its lower end and is adapted to be inserted into the sleeve 29, said bead resting upon the upper edge of the sleeve and thereby supporting 85 the said pipe in proper relation to the shoe B. It can readily be comprehended that all of the water precipitated upon the inner walls of the cold air return duct 15 is collected by the gutter 36 and discharged 90 through the leader 38 into the compartment 95 27 of shoe B, where the same may be readily drained from the system through the waste pipe 28. The air on passing into the shoe is thereby freed from any drops or large 100 globules of water which might otherwise drop from the lower edge of the duct 15 into the shoe proper and be picked up thereby, and also eliminating dripping noises.

In addition to the gutter 36 for removing the surplus water from the system I employ 105 an arcuate baffle 40 which is situated within the space 14 in the furnace A. This baffle has connected to it a drain-board 41 adapted to extend through the opening 25 and into the compartment 27 of shoe B, where said 110 drain-board is formed with a depending lip 42 adapted to overhang the wall 26 of neck 24. This structure is further supported upon a block 43 situated within the furnace 115 and resting upon the floor in such a manner that the baffle 40, which is inclined in relation to the drain-board 41, slopes toward the ash pit section 10 of the furnace and leans against the same. With this device the 120 larger globules of water present in the humidified air are caused to be precipitated against the baffle 40 as the air changes direction in leaving the shoe B and entering the space 14 within the furnace A. Such water precipitated against this baffle is drained by 125 means of the drain-board 41 back into the compartment 27 where it is carried away by the waste pipe 28 as previously described. It can therefore readily be seen that all of the surplus water is removed from the air 130

entering the furnace so that when the humidified air is discharged into the room, the same is comparatively free from larger globules of water and is in a highly suitable condition.

My invention is particularly advantageous in that it serves to remove the surplus water from the humidifying system and from the air discharged therefrom, so that the air upon entering the room is properly conditioned, thereby preventing corrosion of the furnace and injury and disfigurement of the articles within the room where the air is discharged. At the same time the undesirable noise from the dripping of the water in the shoe is eliminated.

Changes in the specific form of my invention, as herein disclosed, may be made within the scope of what is claimed without departing from the spirit of my invention.

Having described my invention, what I claim as new and desire to protect by Letters Patent is:

1. In combination with the casing of a furnace, a shoe connected therewith and having an opening along the top thereof, a sleeve attached to said opening and extending inwardly to said shoe, and a peripheral gutter attached to the lower end of said sleeve and leading to one side of said shoe, a duct forming the cold air return of said furnace mounted in said sleeve, and a spray nozzle situated in said duct.

2. In combination with the casing and a vertical duct forming the cold air return of a furnace, a shoe connected to said casing and having an opening in the top thereof, a sleeve mounted in said opening and depending within said casing, said sleeve being adapted to receive said cold air duct, a spray nozzle situated within said cold air return, a gutter formed along the lower edge of said sleeve and inclined toward a wall of said shoe, and a leader connected with said gutter and extending toward the base of said shoe.

3. In combination with the casing and vertical duct forming the cold air return of a furnace, a shoe connecting said duct with said casing, a spray nozzle situated within said duct, and a gutter in said duct beneath said spray nozzle and above the bottom of said shoe.

4. In combination with the casing and a vertical duct forming the cold air return of a furnace, a shoe having a neck connected with the said casing, said neck being raised above the base of said shoe, an opening in the top of said shoe communicating with said duct, a spray nozzle situated within said duct, and a drain in the bottom of said shoe situated below said neck, and a baffle situated within said furnace and inclining toward the wall thereof and having a portion connected therewith forming a drain-

board, said drain-board portion extending over said neck and discharging into said shoe proper.

5. In combination with the casing and a duct forming the cold air return of a furnace, a shoe being rounded at one end and formed with a neck at its other end connected to said casing, a circular opening in the top of said shoe, a circular sleeve formed of sheet metal being doubled back for a portion thereof to provide an annular shoulder, said sleeve extending into said opening and depending within said shoe with the shoulder thereof resting upon the top of said shoe, the depending portion of said sleeve being turned inwardly to form an annular gutter along the lower end of said sleeve, said sleeve being arranged to receive the end of said circular duct, and a leader connected with said gutter at the lowermost portion thereof, and extending toward the bottom of said shoe.

6. In combination with the casing and a duct forming the cold air return of a furnace, a shoe being rounded at one end and formed with a neck at its other end connected to said casing, a circular opening in the top of said shoe, a circular sleeve formed of sheet metal being doubled back for a portion thereof to provide an annular shoulder, said sleeve extending into said opening and depending within said shoe with the shoulder thereof resting upon the top of said shoe, the depending portion of said sleeve being turned inwardly to form an annular gutter along the lower end of said sleeve, said gutter inclining toward the curved end of said shoe, said sleeve being arranged to receive the end of said circular duct, and a leader connected with said gutter at the lowermost portion thereof, and extending toward the bottom of said shoe.

7. In combination, a furnace having a casing and a vertical duct forming the cold air return connected therewith near the bottom of said casing, a spray nozzle situated within said duct above the bottom thereof, and a gutter at the lower end of said duct beneath said spray nozzle.

8. In combination with the casing and vertical duct forming the cold air return of a furnace, a shoe connecting said duct with said casing, said shoe having a neck raised above the base of said shoe, and a baffle within said casing adapted to drain water from the interior of said furnace into said shoe and through said neck.

9. In combination with the casing and a vertical duct forming the cold air return of a furnace, a shoe connecting said duct and casing, and a baffle within said casing adapted to drain water into said shoe.

In testimony whereof, I have signed my name to this specification.

DANIEL HANDELAN.
